INVENTOR:

H. C. Bascom

UNITED STATES PATENT OFFICE.

H. CLAY BASCOM, OF TROY, NEW YORK.

DESIGN FOR A COOKING-STOVE.

SPECIFICATION forming part of Design No. 15,763, dated February 3, 1885.

Application filed October 20, 1884. Term of patent 7 years.

To all whom it may concern:

Be it known that I, H. CLAY BASCOM, a citizen of the United States, residing at the city of Troy, in the county of Rensselaer and State of New York, have invented and produced a new and original Design for Cooking-Stoves, of which the following is a specification, reference being had to the accompanying engraving of a cooking-stove having said design.

10 This design embraces several new and distinctive parts and combinations of parts which go to make up the whole design, as hereinafter specified.

One integral part of this design is the border ornamentation of the oven-door B, which ornamentation consists of the four compound corner ornaments, C, each having the inclined double ornamented bands h, with lobate ornaments at the ends, and lateral scroll-leaves i, and the four double or loop-like beadings which extend along the border of the door between the said compound corner ornaments.

Another distinct part is the shape and ornamentation of the panel-plate A on the oven-door, the same being of a general oblong quadrilateral shape, with the two straight side edges, a, parallel to each other, the concavely-curved corner recesses, b, and the two end edges c, curved concavely toward the middle

30 into the projecting points c', and having the flat surface d, with straight incut lines extending obliquely from the corners and dividing the surface into two opposite obtuse triangular sections, in which are the compound incut ornaments e, and two opposite acute triangular sections having the compound ornaments f and the central oblong lobate ornament, as shown.

A further distinctive part of this design is 40 the shape and ornamentation of the oven-door, the same being of the form shown, with the swelling surface g, and having the raised panel ornament A, consisting of the parts a, b, c, c', d, e, and f, as above specified, in combination with the compound corner ornament, C, having the parts h and i, as shown. Another part relates to the shape and ornamentation of the raised panels D and E, of rectangular form, with the swelling surface j, and

having the central compact floral ornament, 50 k, and the compound corner ornaments, l, as shown. Another part relates to the shape and ornamentation of the rear extension-plate, F, of the form shown, and having the raised rectangular panel E and the compound ornament G, as shown. Another part relates to the shape and ornamentation of the front door, H, consisting of the curved upper portion, m, having the three mica lights n, with molded corners, and the adjacent ornamentations o, the inclined name-band p, and the flat upright lower portion, q, having the row of oblong apertures r, with curved upper corners, and the intermediate double-band ornamentations, s, as shown. Another part is the 65 shape and ornamentation of the legs I, consisting of the large swelling portion t, having the ring-form ornament u, central floral ornament, v, upper corner ornaments, w, contracted and concavely-curved part x, and the 70 foot y.

The whole design embraces the shape and ornamentation of the top plates, the side, including the panel-plate A, door B, panel D, and extension F, the front, including the door 75 H and forward hearth-extension, the bottom plate, and the legs.

I claim as new—

1. In a design for a stove, the border ornamentation of the oven-door, consisting of the 80 corner ornaments, C, having the ornamented double bands h, with lobate end ornaments and lateral scroll-leaves i, and the double beadings extending along the border between said corner ornaments, as shown and described. 85

2. In a design for a stove, the shape and ornamentation of the panel-plate A, embracing the edging a b c c' and flat surface d, with the incut oblique lines, compound ornaments e f, and the central lobate ornament, as shown 90 and described.

3. In a design for a stove, the shape and ornamentation of the door B, the same being of the form shown, with the swelling surface g, and having the ornamentations A a b c c' d 95 e f and C h i, as shown and described.

4. In a design for a stove, the shape and ornamentation of the panels D and E, embrac-

(over)

- ing the parts *j*, *k*, and *l*, as shown and described.
5. In a design for a stove, the shape and ornamentation of the rear extension, *F*, embracing the parts *E* and *F*, as shown and described.
6. In a design for a stove, the shape and ornamentation of the front door, *H*, consisting of the parts *m n o p* and *q r s*, as shown and described.
- 10 7. In a design for a stove, the shape and ornamentation of the legs, consisting of the parts *t u v w x y*, as shown and described.
8. The design for a cooking-stove, embracing the top plates, the side, the front, the bottom plate, and the legs, shaped and ornamented substantially as shown and described. 15
- In testimony whereof I hereunto set my hand, in the presence of two subscribing witnesses, this 17th day of October, 1884.

H. CLAY BASCOM.
